the spring arch support having a base flange and being centrally situated on wooden heel-plate 5. The base part of the arch support has a slightly bent base flange, provided with an oval hole 3, adapted to receive a nail 4, and a central hole 14, which is centrally situated on the heel-plate 5. The heel-plate 5 is provided with a plurality of nail holes 6, adapted to receive the nail 4, and a central hole 11, through which the screw 12 passes, as hereinafter described.

RECORDED IN ST. LOUIS, MO.

This improved device is a shoe heel fastener, the combination of an inside metal plate having a small countersunk hole centrally positioned therein, and lying inside the shoe at the heel thereof; a spring arch-support secured to the outside of the shoe sole, in the arch thereof, and terminating in an integral widened portion at the heel, said portion forming a heel plate and being secured up-

UNITED STATES PATENT OFFICE

LADY'S SHOE HEEL FASTENER

Magnus H. Grinde, Tacoma, Wash.

Application August 10, 1935, Serial No. 35,609

1 Claim. (Cl. 36—76)

This invention relates to devices for securing the heel to a shoe, and especially the high heel commonly known by such names as the "French", "Cuban", "Spike", and "Boulevard" heel.

The objects of my invention are to provide, first, a strong and firm union or bond between the wooden heel and the shoe; second, a means for connecting the heel to the arch support of such a shoe; third, a means for protecting the foot and hose of the wearer from excessive wear on such securing means; and fourth, a connecting means which is cheap to make, easy to apply, and effective in use.

15 A further object is to provide a device which may be used in shoes into which it was not originally built.

I attain these and other objects by the devices and arrangements illustrated in the accompanying drawing, in which—

Fig. 1 is a side view of a lady's shoe, partly in section, with the parts dissociated in order to reveal the construction; Fig. 2 is a perspective view of the combined arch support and heel fastener; Fig. 3 is a plan view of the inside plate of the heel fastener; Fig. 4 is a rear elevation of the combined arch support and heel fastener; and Fig. 5 is a section of the arch support, taken at the line 5—5 in Fig. 2.

30 Similar numerals of reference refer to similar parts throughout the several views.

It has long been a difficult problem to securely fasten a high heel to a lady's shoe without adding substantially to the bulk and destroying the neatness of the design of the shoe, with the result that the loss of a heel is a comparatively common occurrence. These shoes usually have a steel spring arch support incorporated into them.

Referring to the drawing, it will be seen that the spring arch support 1, which is of the usual curved section (Fig. 5), is provided with a flattened portion 2 at its front end, said part 2 being provided with a suitable hole 3 adapted to permit a nail 4 to pass therethrough, and with a heel plate 5 at its rear end. The heel plate 5 is preferably formed integral with the arch support 1 and is dished downward slightly, as shown in Figs. 1 and 4. The heel plate 5 is provided 50 with a plurality of nail holes 6, adapted to permit the nails 7 to pass therethrough to secure the plate 5 to the leather 8 of the shoe. This heel plate 5 is also provided with two downturned sharp-pointed prongs or lugs 9, adapted to be driven into the wooden heel 10, and with a cen-

tral hole 11, through which the securing screw 12 passes, as hereinafter described.

In some cases the heel plate 5 is made separate from the arch support 1, extending for instance only to the line A—B in Fig. 2, such form 5 being especially adapted for use in shoes into which my improved fastener was not originally built.

An inside plate 13 (Figs. 1 and 3) is provided with a central hole 14, corresponding in position 10 with the central hole 11 in the heel plate 5. The plate 13 is slightly dished downward to conform to the shape of the undersurface of the wearer's heel, and is also countersunk around the said hole 14. The hole 14 is adapted to permit the 15 wood screw 12 to pass through it. The said wood screw 12 therefore passes through the inside plate 13, the leather 8 of the shoe, the heel plate 5, and into the wood of the heel 10. The head of the screw 12 lies snugly in the countersunk part 20 of the plate 13. The usual covering strips 15 of leather are, of course, also provided.

Assembly

The arch support 1 is secured in place in the 25 shoe by driving the nail 4 through the hole 3, and the nails 7 through the holes 6 of the heel plate 5. All these nails are suitably clinched on the inside of the shoe, in the usual manner. Then the heel 10 is forced over the prongs 9 30 and is held in place thereby. Then the inside plate 13 is placed in position in the shoe and the screw 12 is passed through the holes 14 and 11 and is screwed into the heel 10. This screw 12 therefore tightly draws the heel 10 into position and clamps the shoe leather 8 and the heel plate 5 between the heel 10 and the inside plate 13, and firmly holds all the parts together; the prongs 9 keeping the heel 10 from twisting on the screw 12.

It is, of course, to be understood that many variations may be made in the details of construction of my improved heel fastener, without departing from the spirit of my invention as outlined in the appended claim.

Having described my invention, what I claim and desire to secure by Letters Patent, is:

In a shoe having a sole and a heel, the combination of an inside metal plate having a small 50 countersunk hole centrally positioned therein, and lying inside the shoe at the heel thereof; a spring arch-support secured to the outside of the shoe sole, in the arch thereof, and terminating in an integral widened portion at the heel, said portion forming a heel plate and being secured up- 55

ward to the shoe sole by nails therethrough, said nails being covered by said inside plate, and said heel plate being provided with a small central hole registering with the countersunk hole in said inside plate; a wooden heel; prongs, integral with said heel plate and extending downward therefrom, entering the upper surface of said wooden

heel; and a wood screw passing through the small registered holes in the inside plate and the heel plate and entering said wooden heel and drawing the heel up into tight contact with said heel plate and clamping the sole between the inner plate and the heel plate. 5
